US0D1106335S

(12) **United States Design Patent** (10) Patent No.: **US D1,106,335 S**
(45) Date of Patent: ** Dec. 16, 2025

(54) **GAMING MACHINE**

- (71) Applicant: **Aristocrat Technologies, Inc.**, Las Vegas, NV (US)
- (72) Inventors: **Stephen Shaffer, Jr.**, Las Vegas, NV (US); **Frank Rodriguez**, Las Vegas, NV (US); **Bruce Urban**, Las Vegas, NV (US); **Alfred Thomas**, Ventura, CA (US); **Rajendrasinh Jadeja**, Las Vegas, NV (US); **Matthew McKay**, Henderson, NV (US); **Joseph Kaminkow**, Las Vegas, NV (US); **Marenz Ganadillo**, Las Vegas, NV (US); **Ariel Turgel**, San Francisco, CA (US); **Daniel Harden**, Palo Alto, CA (US); **Elliott Ortiz**, San Francisco, CA (US); **Hirotomi Teranishi**, San Jose, CA (US)
- (73) Assignee: **Aristocrat Technologies, Inc.**, Las Vegas, NV (US)

(**) Term: **15 Years**(21) Appl. No.: **29/963,836**(22) Filed: **Sep. 19, 2024****Related U.S. Application Data**

- (63) Continuation of application No. 29/838,036, filed on May 10, 2022, now Pat. No. Des. 1,072,944.
- (51) **LOC (15) Cl.** **21-03**
- (52) **U.S. Cl.**
USPC **D21/369**
- (58) **Field of Classification Search**
USPC D21/324, 325, 329, 332, 333, 349, 336, D21/356, 365, 369, 370, 371, 385, 397; D14/305-307, 312, 336, 354, 373
CPC G07F 17/3211

CLAIM

The ornamental design for a gaming machine, as shown and described.

DESCRIPTION

FIG. 1 is a front, top perspective view of a gaming machine showing our new design according to a first embodiment; FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a rear, bottom perspective view thereof;

FIG. 8 is a front, top perspective view of a gaming machine showing our new design according to a second embodiment; FIG. 9 is a front view thereof;

FIG. 10 is a rear view thereof;

FIG. 11 is a right side view thereof;

FIG. 12 is a left side view thereof;

FIG. 13 is a top plan view thereof;

FIG. 14 is a rear, bottom perspective view thereof;

FIG. 15 is a front, top perspective view of a gaming machine showing our new design according to a third embodiment;

FIG. 16 is a front view thereof;

FIG. 17 is a rear view thereof;

FIG. 18 is a right side view thereof;

FIG. 19 is a left side view thereof;

FIG. 20 is a top plan view thereof;

FIG. 21 is a rear, bottom perspective view thereof;

FIG. 22 is a front, top perspective view of a gaming machine showing our new design according to a fourth embodiment;

FIG. 23 is a front view thereof;

FIG. 24 is a rear view thereof;

FIG. 25 is a right side view thereof;

FIG. 26 is a left side view thereof;

FIG. 27 is a top plan view thereof; and,

FIG. 28 is a rear, bottom perspective view thereof.

The dashed broken lines in the figures illustrate portions of the gaming machine that form no part of the claimed design. In FIGS. 15-28, the gaming machine is shown with a symbolic break in its length. The pairs of adjacently-spaced dot-dot-dash broken lines in FIGS. 15-28 form no part of the claimed design. The appearance of any portions between such pairs of adjacently-spaced dot-dot-dash broken lines forms no part of the claimed design.
